ROOFING

Michael W. Papesh, Essex, Md., assignor to The Ruberoid Co., Bound Brook, N. J., a corporation of New Jersey

Application May 12, 1950, Serial No. 9,891

Term of patent 14 years

(Cl. D68—1)

To all whom it may concern:

Be it known that I, Michael W. Papesh, a citizen of the United States, residing at Essex, Baltimore County, State of Maryland, have invented a new, original, and ornamental Design for a Roofing, of which the following is a specification, reference being had to the accompanying drawing, forming part thereof, in which:

I claim:

The ornamental design for a roofing, substantially as shown.

MICHAEL W. PAPESH.
